FILAMENT FOR THERMIONIC TUBE

Waldemar Wehnert, Berlin, Germany, assignor
to Telefunken Gesellschaft für Drahtlose Tele-
graphie m. b. H., Berlin, Germany, a corpora-
tion of Germany

Application July 23, 1932, Serial No. 624,252
In Germany August 13, 1931

7 Claims. (Cl. 250—27.5)

In thermionic tubes operating with relatively large plate currents of the type, for instance, as found in the power stages of receiver apparatus it is customary to use cathodes or filaments comprising a plurality of parts or sections, the latter resulting in forms of arrangement resembling the letters V, N or W.

In the drawing Figs. 1a—c show these forms of filament, and it is also indicated therein in what way the filament supply and also the grounding is effected in these filaments when alternating current is employed by ways and means well-known in the prior art.

It has been found that in so far as freedom from hum is concerned in tubes directly heated with alternating current, it is solely the V-shaped filament that will satisfy all requirements, whereas in the case of N- and W-shaped filaments, even if the potentiometer ground is shifted to an extreme position in either direction, there still remains an unduly strong humming noise. Examining the shape of the potential of the W-shaped filament of Fig. 1c, as indicated schematically in Fig. 2 at right angles to the filament plane, this action will be readily understood for what such a filament represents is a dipole having a pronounced outward action.

According to the present invention this drawback is obviated by that in each case the two filament parts or sections presenting a maximum potential difference are disposed directly adjacent to each other. What is of greatest advantage in this connection is that the adjacent filament parts have the same fall of filament potential, and that the cathode parts being geometrically farthest removed from the median line through the system constitute the electrical center of the filament system.

By a filament disposition of the kind as disclosed in the invention it is feasible also in the case of N- and W-shaped filaments to so far minimize the residual hum that it will be of about the same order of magnitude as in the V-shaped filament.

Fig. 3 by way of example illustrates an arrangement of a pair of inverted V-shaped filaments, comprising the sections e, f, g and h, the inner sections f and g having the lead-in conductors l and m respectively connected thereto, and the outer sections e and h being electrically connected together in series as shown. With this arrangement it will be observed that the maximum potential difference exists between the inner adjacent sections f and g and that the outer sections e and h constitute the electrical center of the filament system. Fig. 4 illustrates the shape of the

potential inherent in such an arrangement, whence it can be readily seen that the disposition of the filament as here disclosed represents a dipole which does not have any effective outward action with the result that the desired freedom from humming is secured. 5

What is claimed is:

1. A filament construction for a thermionic tube comprising a pair of inverted V-shaped filaments arranged side by side in substantially the same plane and electrically connected in series, and a pair of lead-in conductors connected to the inner adjacent legs of said filaments for supplying alternating heating current thereto. 10

2. A filament construction for a thermionic tube comprising a pair of inverted V-shaped filaments arranged side by side in substantially the same plane, a connection between the outer legs of the filaments, and a pair of lead-in conductors connected to the inner adjacent legs of said filaments for supplying alternating current thereto. 15

3. A multiple filament for a thermionic tube, comprising two pairs of electron emitting portions, the electron emitting portions of each pair being connected together only at one of their ends, 25 one portion of each pair being arranged in close proximity and the other portion of each pair being arranged farther apart and electrically connected together, and connections to the closely adjacent portions of the filament for supplying alternating 30 current thereto.

4. A filament construction for a thermionic tube comprising four coplanar electron emitting sections, the first and second sections being electrically connected together at one of their ends, the 35 third and fourth sections being similarly electrically connected together at one of their ends, a connection between the first and fourth sections at their other ends, and lead-in conductors connected to the second and third sections at their 40 other ends.

5. A filament for a thermionic tube, comprising a plurality of sections electrically connected in series, and a pair of conductors connected to two of these sections for connection to an energizing 45 source, the arrangement being such that said sections which have between them a maximum potential difference are so disposed that they are at closer proximity to each other than the remaining sections are to each other. 50

6. A filament for a thermionic tube, comprising four electron emitting sections electrically connected in series, and a pair of conductors connected to two of these sections for connection to an energizing source, the arrangement being such 55

that said sections which have between them a maximum potential difference are so disposed that they are at closer proximity than the two filament sections which have between them the 5 least potential difference.

7. A filament for a thermionic tube, comprising a plurality of sections electrically connected

in series and so arranged that the two terminal sections to which the energizing source is adapted to be connected are disposed adjacent one another, and the intermediate sections of the electrical series being disposed farther apart and on either side of the terminal sections.

WALDEMAR WEHNERT.
